WILLIAM COOMBES, OF NOTTINGHAM, ENGLAND

WARP OR STRAIGHT-BAR KNITTING MACHINE AND THE PRODUCTION OF FABRICS THEREON

Application filed July 7, 1927, Serial No. 203,926, and in Great Britain December 15, 1926.

This invention has reference to improvements in warp knitting machines and the production of fabrics thereon and has for its principal object to provide means whereby fabrics composed of weft threads extending continuously in a transverse direction from selvedge to selvedge and locked by knitted loops composed of warp threads can be produced on such machines in a more simple and 10 expeditious manner than heretofore.

The invention is concerned particularly but not exclusively with the manufacture of fabrics such as cleaning cloths, sponge cloths and the like from poor quality yarns. It is 15 well known that considerable difficulty exists in the use of such yarns for the manufacture of fabrics owing to the inherent tendency of same to break. In the use of yarns generally in knitting machines tension must of necessity 20 be applied and in the laying of weft threads to be held by chains of warp threads it has been customary to prevent fouling of the weft threads with the needles by applying tension to such threads. In the manufacture of 25 fabrics from poor quality yarns this procedure is obviously impossible and further means must be provided for preventing fouling. The motion of the weft thread carrier members must be as smooth as possible and 30 this requirement is particularly emphasized when the laying of the weft thread is interrupted at predetermined intervals.

For the purpose of more fully describing the nature of this invention, reference will 35 now be made to the accompanying drawings, wherein:

Figure 1 is an end elevational view of a machine in accordance with this invention, the one end frame of the machine being re- 40 moved.

Figure 2 illustrates in front elevation the weft carrier commencing the return motion after laying the weft, the interceptor at this 45 position being about to receive the weft.

Figure 3 is a plan view of Figure 2. Figure 4 is a perspective view of a fragment of the machine showing the disposition of the needles, fixed grid and movable grid.

Figures 5, 6 and 7 are detail views showing 50 in side elevation successive steps in the op-

eration of the moving grid upon a weft, the weft interceptor being shown coming into operation in Figure 7.

Figure 8 illustrates in elevation means for transmitting motion to a weft carrying device 55 and for enabling such weft carrier to be retained from movement when required.

Figure 9 is an enlarged detail view of catch mechanism employed in connection with the weft carrying means shown in Figure 8. 60

Figure 10 is a detail view illustrating means for operating the catch mechanism shown in Figures 8 and 9.

Figure 11 illustrates means for selectively operating a plurality of catch mechanisms 65 employed in connection with a plurality of weft carriers.

Figure 12 is an end elevational view of Figure 11 looking in the direction of arrow X. 70

Figures 13 and 14 illustrate in side elevation and plan respectively the operation of a weft deflector employed in an alternative construction of machine for detaching the weft from its carrier. 75

In the specification the expression "front of the needles" means the plain side of the needles and the expression "back of the needles" means the side having the beard or latch. The expressions "warp" and "weft" 80 are to be interpreted as embracing single threads or two or more threads.

In one method of carrying out this invention the needles 1, preferably latch needles, are mounted on a needle bar 2 and the warp threads 3 are passed through guides 4 actuated to lap their threads round the needles 1 which reciprocate to produce knitted chains in accordance with known practice. 85

The weft 5 is drawn from a conveniently located supply by a weft carrier 6 mounted to traverse behind the needles and conveniently extending downwardly to a position somewhat above the highest point to which the needles rise. 90

Positioned at the rear of the needles and extending substantially rearwardly and upwardly from the upper rear edge of the knocking over or work bar 7 (such bar in accordance with customary practice being 100

positioned immediately in front of the needles and extending upwardly above the lowest position occupied by the top of the needles) is a fixed or stationary grid 8. Conveniently such grid may be composed of wires or plates, the individual wires or plates alternating with the needles 1 and having between them a space sufficient to allow the needles and warp threads 3 to operate freely.

10 In combination with said stationary grid 8 is a movable grid 9 which may also be composed of wires or plates. Further the wires of such latter grid 9 may be intermediate of the wires of the stationary grid 8 and the movable grid 9 may conveniently be actuated so that any point in the foremost line of the grid describes a circle *a* the centre of which may be approximately midway between the line of traverse of the weft thread carrier 6 and the rear edge of the work bar 7.

15 If the movable grid is composed of wire, same may be formed from one continuous length bent to provide the required parallelly spaced forwardly projecting portions and 20 clamped to the grid bar 9^b by a clamping strip 9^c. The wire, which is of round section, has the advantage of having no edges or corners engaging with the weft.

25 A weft carrier 6 is positioned to the rear and above the needles 1 and actuated to traverse in any convenient manner, but preferably the motion of such carrier is harmonic motion.

30 Such carrier 6 in traversing lays the weft 5 behind the needles 1 and either within the space enclosed by the path of the movable grid 9, or without and above such space. In the latter case the carrier is depressed at the end of each stroke in order to bring the weft 35 within the area of action of the movable grid, and such weft is arrested in its fall even if under no appreciable tension by the fixed grid 8 and is retained by such grid in a position clear of the needles 1.

40 45 In practice it is found that there is a tendency for the commencement of each successive length of weft laid to foul the needle or needles at or near the end of the fabric at which such length commences, and in order 50 to safeguard against this, interceptor members 10 are provided.

55 There is one of such members 10 located beyond each edge of each width of fabric and the manner in which such members function will be more fully described hereafter.

60 As each successive length of weft is laid by the carrier 6 and positioned on or above the fixed grid 8 such length is moved forwardly and downwardly along such grid by the movable grid 9 which is actuated to lay the weft on the work bar 7 immediately in front of the needles 1, which needles then rise and engage the warp threads forming knitted loops embracing the weft in a well known manner. The movements of the movable

grid 9 are preferably so timed and actuated that the lengths of weft 5 are not moved forwardly and downwardly until the needles 1 have moved below the fixed grid so that risk of the weft fouling with the needles during such time is eliminated.

70 As previously stated there is a tendency for the commencement of each successive length of weft to foul the end needle or needles, and to assist in overcoming this the movable grid 9 is preferably extended at each lateral extremity beyond the end needles so that each successive length of weft laid on the work bar extends beyond such needles.

75 After the placing of each length of weft on the work bar and as the carrier 6 commences to traverse in a direction opposite to that in which such length was laid, the free weft beyond the width of the fabric is caused to form a loop embracing the last wire 9^a of the movable grid 9 on that side, as shown in Figure 2.

80 The interceptor 10 as above described which has a suitably formed bend or nose 10^a is now caused to move into a position between the outermost wire 9^a of the movable grid 9 and the next adjacent wire, thereby pressing back the weft thread 5 away from the path of the needles, and as the movable grid 9 recedes to assume a position ready for moving the next 85 length of weft in front of the needles it releases the said loop of weft and allows it to be drawn towards the centre of the fabric by the motion of the weft carrier 6 until such loop is arrested by the interceptor 10. It follows that the line taken up by the weft now 90 leads to the weft carrier from a point on the upper edge of the interceptor 10 higher and farther back than the point where the weft leaves the fabric and the risk of fouling the 95 end needles is avoided. After a sufficient time to allow the needles to fall below the point at which fouling could occur, the interceptor 10 is withdrawn and the loop of weft released from it so that a perfect sel- 100 vedge can be produced.

105 The motions of the interceptor 10 may be produced from the main-drive shaft 11 by an eccentric through the medium of eccentric rod 12 and two armed lever 13. Other 110 suitable means may, however, be incorporated for operating said interceptor.

115 Means are provided for interrupting the laying of weft while continuing the knitting of warp threads. In one arrangement a sleeve or collar 14 slidably mounted upon a horizontal rod 15 extending lengthwise of the machine above the level of the needles 1 and to the rear of said needles has imparted there- 120 to a reciprocatory motion upon said rod from an upwardly extending oscillating arm 16 or the like at the one end of the machine through the intermediary of a link connected at 17 between the arm and sleeve. The oscillating arm 16 which is preferably operated from a 130

crank 18 through link 19 and transmits harmonic motion to the reciprocating sleeve 14 may be composed of a hollow metal tube braced by diagonally disposed wire stays 18^a held in tension on each side of the tube, thus combining lightness with strength. The reciprocating sleeve 14 carries a laterally projecting arm 14^a.

A weft thread carrier in the form of an 10 arm 6 having a thread-accommodating eye or loop at its end,—which carrier is adapted to be traversed across the machine to lay the weft,—is mounted upon a sleeve-like part 20 which in turn is slidably mounted upon a 15 second horizontal rod 21 extending parallel with the first rod 15. To an upstanding part or parts on this carrier sleeve 20 is pivoted at a position intermediate of its ends a hook-like catch 22 which extends longitudinally of the 20 sleeve. This catch may comprise a plate having a bevelled nose 22^a the arm 14^a projecting from the continually reciprocating sleeve 14 being normally accommodated on the under-side of the catch at the back of the nose and 25 the catch being normally held in engagement with said arm 14^a by spring means 23. When so engaged, the weft carrier is traversed to and fro in unison with the aforesaid reciprocating sleeve, thus laying the weft.

30 In order to interrupt the laying of the weft a small rotatably or pivotally mounted finger rod 24 suitably located at one end of the weft traverse is actuated at intervals by high links 25 on a travelling chain 26 or by projections 35 on a rotary drum to move into the path of and coact with an inclined tail portion 22^b of the pivoted catch 22 to depress said tail. This raises the hook end 22^a and releases therefrom the arm 14^a of the reciprocating sleeve 14 40 which then traverses without the weft carrier sleeve 20 which remains stationary at the end of the machine until the finger 24 is again returned by spring or other means to its normal position after passing over the high link 45 on the chain 26, the return of said pin releasing the catch 22 which then moves to the operative position by spring 23.

When the catch 22 is in the operative position, the arm 14^a on the reciprocating sleeve 50 coacts with the bevelled nose of the catch, raises said nose and passes to the rear of the downwardly projecting part thereof, the parts being then connected for traversing the weft until a further high link 25 on the chain 55 26 acts to interrupt again the weft laying.

Advantageously the finger 24 projects laterally in the direction in which the catch 22 is traversed from the one arm of a two-armed lever 27 pivoted at 28, a nose 27^a at the end 60 of the second arm of said lever being maintained by spring or gravity in engagement with the chain 26. The chain is caused to travel intermittently by any suitable means such for example as by a pivoted pawl or 65 clawker 29 operated by eccentric 30 inter-

mittently to rotate a ratchet 31 mounted coaxially with the chain wheel 32.

If desired a plurality of traversable weft carriers may be provided in which case means are incorporated for selectively laying any one or more of the wefts carried thereby, thus enabling the pattern or texture of the fabric produced to be extensively varied by the simple operation of controlling the weft laying.

In a convenient method of accomplishing this an arrangement will be described embodying three weft carriers (see Figures 11 and 12), it being understood, however, that the number may be varied to suit existing requirements.

The lateral arm 14^a carried by the reciprocating sleeve 14 is adapted to coact with catch members 22, one of which is associated with each of three sleeves 20, 20^a, 20^b said sleeves being slidably mounted upon three horizontal rods 21, 21^a, 21^b extending lengthwise of the machine and preferably disposed parallel in one horizontal plane.

The sleeves 20, 20^a, 20^b carry three weft carriers 6, 6^a, 6^b which extend downwardly and are so shaped as to ensure the several threads carried thereby being fed to the required position relatively to the needles.

It will be appreciated that if all of the catch members appertaining to the carriers 6, 6^a, 6^b (or both catches in the case of two carriers) are attached to the lateral arm 14^a of the continuously reciprocating sleeve 14, all of the carriers are traversed to lay the several wefts simultaneously. Should, however, any one or more of the catches be released from said arm, the carrier or carriers appertaining to the released catch or catches is or are not traversed by the reciprocating member and the laying of the weft or wefts of the said carrier or carriers is or are interrupted.

In order selectively to interrupt the laying of any one or more of the wefts, a plurality of the afore-described rotatably or pivotally mounted finger members 24 are provided, the two-armed levers 27, 27^a, 27^b appertaining to said fingers being acted upon at predetermined intervals by high links 25 on one or more travelling chains 26 or by projections on one or more rotary drums to coact with the tail portion 22^b of any one or more of the pivoted catches 22 and depress said tail, such action raising the opposite end of the catch and releasing therefrom the lateral arm 14^a of the continuously reciprocating member.

It will thus be seen that, depending upon the disposition of the high links or the like, the weft carriers are selectively interrupted in their traversing motion, the carrier or carriers which are disconnected from the lateral arm of the reciprocating sleeve being automatically connected for traversing the weft when the catch engaging finger has passed over a high link by reason of the said lateral

arm passing beneath the bevelled end of the catch and entering the recess beneath same.

In a further modification the interruption of the laying of weft may be effected by disengaging said weft from the carrying means therefor. In such an arrangement the carrier 6 may be provided with an open end 6^a in place of a closed eye, the opening being of such a form that the weft can enter or escape from the carrier when such weft is caused to follow a predetermined path between the edge of the fabric 33 and a fixed guide 34 suitably placed above the path of the carrier (Figures 13 and 14). While weft is being laid the weft thread 5 passes from such fixed guide 34 direct to the weft carrier 6 and thence to the edge of the fabric 33. When it is desired to interrupt weft laying a deflecting member 35 operating between the fixed guide 34 and the weft carrier 6 is brought into operation by any suitable mechanism in such a manner that the path of the weft from the deflecting member 35 to the edge of the fabric 33 coincides with the opening in the end 6^a of the weft carrier 6 so that when the weft carrier 6 begins its next stroke the weft is not carried with it. The deflecting member 35 may be withdrawn from the weft 5 at any convenient point in the cycle of motions preferably at or near the end of the stroke, allowing the weft to resume its normal line which crosses the path of the weft carrier in such a manner as to be engaged by its end 6^a and carried with it on the next ensuing stroke.

The operation of the deflector 35 may be accomplished from a travelling chain or band to which motion is transmitted from the main drive 11 of the machine through suitable means. A spring may be provided to return the deflector to the vertical position.

The shogging of the warps 3 may be effected from the main drive shaft 11 in any suitable or known manner.

The tensioning of the warps and wefts and the feeding of same to the machine may be accomplished in any convenient or known manner.

The take up of the fabric may also be effected in any known manner, say for example by means of the roller indicated at 36 in Figure 1.

The machine in accordance with this invention is particularly applicable for manufacturing fabric having at predetermined intervals a lateral band or division composed of a number of courses void of wefts, at which bands the fabric is adapted to be subsequently divided.

Claims:

1. In a warp knitting machine for the production of fabrics composed of weft threads extending continuously in a transverse direction from selvedge to selvedge and locked by knitted loops composed of warp threads, in combination, a needle bed, means for supply-

ing warp threads to the needles, a weft thread carrier, a continuously reciprocating member, a pivoted catch mounted on said weft thread carrier and adapted to engage with said reciprocating member to cause same to traverse the said carrier and lay the weft thread behind the needles, an inclined surface on said catch member, a selectively removable member with which the said inclined surface is adapted to engage pivotally to displace the said catch and release the said weft thread carrier from the reciprocating member, and means for moving the laid weft thread to the front of the needles.

2. In a warp knitting machine, in combination, a needle bed, means for supplying warp threads to the needles, a weft thread carrier, a continuously reciprocating member, a spring influenced catch member pivoted intermediate of its extremities mounted on said carrier and adapted to engage with said reciprocating member to cause same to traverse the said carrier and lay the weft thread on a fixed grid to the rear of the needles, an inclined tail portion on said catch member, a rod member carried by a pivoted lever and projecting in the direction in which the weft carrier is traversed, said inclined tail portion of the catch member being adapted to move into engagement with the said rod to release the weft carrier from the said reciprocating member, controlling means for selectively displacing the said pivoted lever and rod into and out of the path of the said catch member, a movable grid intermeshing with the fixed grid and adapted to move the weft thread laid on said fixed grid to the rear of the needles, and an interceptor member engaging the weft at each selvedge to prevent same fouling the needles.

3. In a warp knitting machine, in combination, means for supplying warp threads to the needles, a plurality of weft thread carriers, a continuously reciprocating member, a centrally pivoted catch member mounted on each carrier and adapted to engage with said reciprocating member and be traversed thereby, an inclined tail portion on each catch member, a plurality of parts projecting from a plurality of pivoted levers, the said inclined tail portions of the catch members being adapted to move into engagement with said projections to release their corresponding carriers from the reciprocating member, and an intermittently traversable pattern chain provided with high links adapted selectively to displace the said pivoted levers and their projections into and out of the path of the said carrier catches to select the said carriers for traverse.

WILLIAM COOMBES.
